UNITED STATES PATENT OFFICE.

LYMAN A. WHEAT, OF BATTLE CREEK, MICHIGAN

STEREOTYPE OR ELECTROTYPE CYLINDER FOR PRINTING-PRESSES.

1,008,507.

Specification of Letters Patent. Patented Nov. 14, 1911.

Application filed April 3, 1909. Serial No. 487,674.

To all whom it may concern:

Be it known that I, LYMAN A. WHEAT, a citizen of the United States, residing at the city of Battle Creek, Calhoun county, State of Michigan, have invented certain new and useful Improvements in Stereotype or Electrotype Cylinders for Printing-Presses, of which the following is a specification.

This invention relates to improvements in stereotype or electrotype cylindrical plates for printing presses.

The objects of this invention are: First, to provide a stereotype or electrotype cylindrical plate or printing cylinder which can be readily adjusted in a rotary press. Second, to provide a cylindrical printing plate which can be readily manufactured without the necessity of trimming or boring. Third, to provide means for supporting an electrotype or stereotype cylindrical printing plate in a rotary press. Fourth, to provide an improved construction wherein the metal of a stereotype or electrotype cylindrical printing plate is reinforced to better withstand the strain of high speed.

Further objects, and objects relating to details of construction will appear from the detailed description to follow.

I accomplish the objects of my invention by the devices and means described in the following specification.

The invention is clearly defined and pointed out in the claims.

A structure embodying the features of my invention is clearly illustrated in the accompanying drawing, forming a part of this specification, in which:

Figure 1 is a longitudinal detail sectional view showing one of my improved cylindrical printing plates and its supporting means and the adjacent parts of the printing press, some parts being shown in full lines taken on a line corresponding to line 1-1 of Fig. 3, the dovetail being omitted.

Fig. 2 is a detail longitudinal sectional view showing details of construction of the method of supporting the cylindrical printing plates. Fig. 3 is a transverse sectional view on line 3-3 of Fig. 2. Fig. 4 is a detail view similar to Fig. 1, (the dovetail detail omitted) of a modified form of the supporting means showing a continuous shaft which may be required in certain instances to add to the stability of the structure.

In the drawing, similar numerals of reference refer to similar parts throughout the several views.

Considering the numbered parts of the drawing, the sides of the press 1, 2 are of the usual form and the stereotype or electrotype printing plate 3 is in cylindrical form being a continuous cylinder as appears from reference to Fig. 3. The ends are shaped either in casting or by boring afterward and receive the divided mandrel 4, 5 which are provided with shoulders 4', 5'. This mandrel is driven by the gear 6 and the outer end of the shaft is supported by a bracket 7 containing a suitable bearing. A bushing 9 surrounds the shaft 8 of the mandrel and permits of its adjustment back and forth, which is accomplished by the hand wheel 13, which controls the screw 10 which is in the bracket 11. A lock-nut 12 is provided for retaining the same securely in place. The parts of the mandrel 4 and 5 are provided with shoulders 4' and 5', respectively, to engage the ends of the printing cylinder.

The metal is preferably cast on a steel shell which is cut with dove-tail ways as clearly appears in Figs. 2 and 3, such dove-tail 14 and 15 clearly appearing in these two figures, the said steel shell being a reinforce. The dovetail cuts are straight across on chords of the circle forming the inner surface in the form of an octagon.

Type metal is not adhesive and does not unite with other metals unless there is some special preparation as a flux, and in this device where it is desired to cast the printing surface, it is not possible to make use of any fluxing means as it would cause the metal to adhere to the matrix and would spoil the printing surface. The type metal must be retained in place by what I choose to call a "clench" or clenching means, the same as plaster adheres to metal or wooden lath on the wall of a dwelling. This is what I mean by the expression "clenching" in the claims.

Where it is desired to provide extra support for the cylinder, this is accomplished by a shaft 16, which fits into a hole in the mandrel shaft 8 and is screw threaded at its inner end to clamp the parts on the mandrel together. This shaft is provided with a collar 18 toward the inner end of this shaft so that when it is unscrewed by backing the

- shaft 16 out the collar can be bumped against the mandrel section 5 and the same be sufficiently separated to permit the introduction of the cylinder. A collar 19 is on 5 the other end of the shaft 16, which serves, when the parts are screwed together, to draw the mandrel firmly together to engage and effectively support the stereotype cylinder.
- 10 The cylindrical printing plate may be produced by a stereotype or by an electro-type process or in any equivalent way from type metal.

Having thus described my invention, what 15 I claim as new and desire to secure by Letters Patent, is:

1. In a printing press, the combination of a printing cylinder, in the form of a continuous metal shell; a divided mandrel, 20 the sections thereof being formed for insertion into the opposite ends of said printing cylinder with shoulders to engage the said opposite ends; independent supports for the separate sections of the said mandrel; and means for clamping the mandrel sections into engagement with the opposite ends of said cylindrical shell, coacting substantially as described and for the purpose specified.
- 30 2. In a printing machine, the combination of a divided mandrel, the parts of which are supported on suitable journal bearings; means for driving the same; a shaft extending between the sections of said mandrel 35 screw-threaded at its inner end to couple

the same together; a shoulder on the said shaft for clamping the parts into engagement with the printing cylinder, and a second shoulder for use in driving the mandrel sections apart; and a printing cylinder 40 to be engaged and carried between the parts of said mandrel, coacting for the purpose specified.

3. In a printing machine, the combination of a divided mandrel, the parts of which 45 are supported on suitable journal bearings; means for driving the same; a shaft extending between the sections of said mandrel screw-threaded at its inner end to couple the same together; a shoulder on the said shaft 50 for clamping the parts into engagement with the printing cylinder; and a printing cylinder to be engaged and carried between the parts of said mandrel, coacting for the purpose specified.

4. In a printing machine, a printing cylinder consisting of a shell of strong reinforce metal, having straight transverse dovetail grooves therein on chords of the surface of said cylinder, with a printing face of 60 type metal cast upon the same in a continuous cylinder and clenched into the dovetails of said reinforce metal.

In witness whereof, I have hereunto set my hand and seal in the presence of two 65 witnesses.

LYMAN A. WHEAT. [L. S.]
